UNITED STATES PATENT OFFICE.

GEORGE CROMPTON, OF WORCESTER, MASSACHUSETTS.

IMPROVEMENT IN LOOMS.

Specification forming part of Letters Patent No. 32,123, dated April 23, 1861.

To all whom it may concern:

Be it known that I, GEORGE CROMPTON, of Worcester, State of Massachusetts, have invented a certain new and useful Improvement in Power-Looms; and I do hereby declare that the following is a full, clear, and exact description thereof, reference being had to the accompanying drawings, making part of this specification, in which—

Figure 1 is a front elevation of a loom with my improvement applied. Fig. 2 is an end elevation, and Fig. 3 a plan, of the same.

The same letters indicate like parts in all the figures.

My invention relates to the motion which drives the picker-staff and a method of controlling the action of the same.

In plain weaving, or where only one shuttle is used, the picker-staffs are actuated alternately by cams or their equivalents, so arranged on the cam-shaft of the loom. In looms having drop-boxes at each end of the lathe the uncertainty from pick to pick from which side the shuttle should be driven led to the plan of operating both picker-staffs simultaneously, either drop-box then bringing a shuttle even with the race would be discharged, the picker in the empty box end returning in season for the entrance of the shuttle. This is the arrangement now in common use. Its wear and tear on the pickers and picker-staffs by their useless action at the empty box end and the wasteful expenditure of power incurred has always been considered a great objection and has of late years led to several attempts to overcome the difficulty, the most prominent of which was the subject of a patent issued to James Greenhalgh, March 4, 1856, which consisted of an arrangement governed by a chain, conformable to the pattern of the drop-box chain. In my invention I use no chain, but simply govern the picking on each side of the loom by the presence and absence of the shuttle. When the shuttle-box binder by the presence of the shuttle operates the protector-rod, it in turn disconnects the picking at the opposite or empty box end, whose binder has similar control over the picking at the other end, each shuttle-box having an independent protector-rod, as I shall now proceed to describe.

In the accompanying drawings, A represents the lathe, B B the loom-sides, C and D

the gearing, the loom being constructed with the ordinary drop-box apparatus well known and in common use among weavers. The drawings no not represent the well-known chain for determining the action of the pawl which is used to operate the tappet-wheels.

E is a tappet-wheel attached to a ratchet-wheel F in the usual manner, which is pushed forward one tooth by pawl G by means of the cam H on the shaft I, and thereby depresses the lever J and lifts at the other end by the vertical rod K the series of shuttle-box compartments L and brings the lower box M level with the race of the lathe R'. The same action of the tappet-shaft by a tappet at the opposite end by a duplicate arrangement to that above described lowers the series of shuttle-box compartments N and brings the box O in a line with the race. This box is empty, while the box M at the other end contains a shuttle Q, which presses out the binder R, which in turn forces the protector-finger S, attached to the horizontal rod T, and raises the arm P attached to it, passed under and at right angles with the lathe, and by the connecting-link U lifts the catch V from connection with the lip on the catch-piece W. The box O containing no shuttle, the binder G' being in its normal condition, the protector-rod W' and the finger F' do not raise the catch out of contact with the catch-piece X. This catch-piece, as well as its duplicate W, is keyed fast to its respective shaft. The short and long arms Y Y are cast and attached to a common hub, which is loose on the shaft A'. The shoe B' is keyed fast to the shaft. The time for picking having arrived, the roller C' in the double arm D', by the movement of the main shaft E', strikes the shoe B', which rocks the shaft A' and oscillates the catch-piece X, and by the shoulder or lip comes in contact with the catch K'. This being attached to short arm Y is driven in the direction of the arrow. The long arm Y, being connected to the same, is propelled in the same direction, and by the connection I' at its extremity extending to the picker-staff H' propels at the same time the staff and the picker, and the shuttle is discharged. The picker-staff, by a spring at its foot, is returned to the end of the lathe and draws by the connection the long and short arms Y Y to their original positions. The catch-piece

is also restored to its first position by the spring J'. Simultaneously with the operation above described the shaft L' has made the same movement. Rocking freely through the hub of the arms M'M' and oscillating the catch-piece W, its shoulder or lip passes by without engaging the catch, the short arm to which it is attached and the long arm remain stationary, as does also the picker-staff N'. The catch-piece W and the picker-staff are then returned to their first positions, like their counterparts, as above described. The next movement of the tappet-shaft will bring the boxes O', containing a shuttle, and the empty box P' into a line with the race. The action of the protecting-fingers and the position of the catches will then be reversed from that of the preceding pick, the picker-staff N' being driven when the rocker strikes the shoe Q', the catch being engaged by the shoulder on the catch-piece W, while, the catch being disengaged from the shoulder on the catch-piece X, its respective staff will remain stationary.

S' is a dart or dagger, which is usually employed for liberating the shipper. When there is no shuttle in either box, the arms T' and U' are raised, which allow it to perform this office.

It will be perceived that a shuttle-box containing a shuttle, by the action of its respective protector-rod, renders the picker-staff at the opposite end inoperative, and that if by accident a shuttle should be in each box on a line with the race both staffs would be silent, and consequently avoid a collision, and the picking of them will continue suspended for any indefinite number of picks until one of the shuttles is removed, when the remaining one will be driven by the action of the staff, the one at the other end being silent.

Instead of controlling the picking at each end by the action of the binders of the shuttle-boxes at the opposite ends, each box might govern the picking at its respective side and the same result would be obtained, excepting in the case where two shuttles were opposed, when both picker-staffs would operate and both shuttles would meet, to the manifest injury of the warp. I therefore consider the plan described the best. There are various ways of connecting and disconnecting the cam movement from the picker-staffs from that of the catch and catch-piece above described, and it might be found necessary to do so perhaps in applying to the many kinds of picking motions. My invention may be applied to drop-boxes, as herein described, to rotary and horizontal sliding boxes, or to a series of boxes working upon the arc of a circle; but so long as the action of the shuttle by its exit from or entrance into a box or by the presence or absence of a shuttle in one or both boxes, when brought in a line with the race, does by any instrumentality engage or disengage the picking mechanism with or from one or both the picker-staffs, the essential and fundamental principle of my invention is preserved.

Having thus fully described my invention, what I desire to claim, and secure by Letters Patent, is—

Controlling the operation of the picker-staffs, substantially as and for the purpose specified.

GEORGE CROMPTON.
